UNITED STATES PATENT OFFICE.

FRANCESCO RESINELLI, OF VADO LIGURE, ITALY.

FURNACE FOR THE PRODUCTION OF CAST IRON AND STEEL.

975,998.

Specification of Letters Patent. Patented Nov. 15, 1910.

Application filed July 2, 1909. Serial No. 505,746.

To all whom it may concern:

Be it known that I, FRANCESCO RESINELLI, a subject of the King of Italy, residing at Vado Ligure, Province of Genoa, in the 5 Kingdom of Italy, have invented certain new and useful Improvements in Furnaces for the Production of Cast Iron and Steel; and I do hereby declare the following to be a full, clear, and exact description of the invention, such as will enable others skilled 10 in the art to which it appertains to make and use the same.

This invention relates to improvements in furnaces for the production of iron and steel 15 and has for its object to provide an apparatus of this nature which will be more efficient than those heretofore produced, and one which will materially lessen the cost of production of iron and steel.

20 To these ends the invention consists in the combinations of the several distinct apparatus and in the details of construction more fully hereinafter disclosed and particularly pointed out in the claims.

25 In order to make clear just how my invention differs from other iron and steel furnaces which have been heretofore proposed, it is said that it is well known to form within the walls at the lower part of a blast 30 furnace or cupola, a chamber and passages extending between the interior of the furnace and the upper and lower parts of this chamber, respectively, so that hot gases pass from the furnace into the lower part of the 35 chamber and are returned from the upper part of the chamber to the furnace. Chlorid of sodium has been placed in the said chamber and heated therein so that the fumes therefrom mingle with the hot gases and 40 pass into the furnace, and the twyers also traverse this chamber so that the air passing through the twyers is highly heated. It has also been suggested to provide a reservoir or fore hearth in combination with this furnace and to cause the heated gases to flow 45 through this reservoir; the pipes conveying air to the twyers may also be arranged in a chamber heated by the metal or gases in the said reservoir. It has moreover been proposed to heat the air for combustion by conducting it downwardly through a regenerator arranged in the furnace shaft or chimney, and through vertical passages in the 50 walls of the furnace leading to the twyers, the regenerator being heated by the com-

bustion of furnace gases withdrawn at a point below the furnace mouth and ignited, at the level of the furnace mouth, in the space into which the charging doors open.

The present invention differs from the 60 above in that it comprises, in combination, a principal furnace, a shaft or chimney, a regenerator, a fore-hearth and an auxiliary preheating furnace for heating reagents as hereinafter described. Gases for heating the 65 furnace last mentioned are withdrawn from the fusion zone of the principal furnace and returned to the chimney whereby the pressure of the gases in the fusion zone is decreased.

70 The said invention also comprises a convenient construction of regenerator adapted for present purposes, and provision is made for supplying combustible gases for heating the air passing through the regenerator in 75 an improved manner so that flaming at the charging mouth, when the feed doors are open, is diminished or prevented.

75 Referring to the accompany drawing:— Figure 1 shows a vertical central section of 80 the improved furnace. Figs. 2, 3, 4 and 5 show horizontal sections taken on the lines *i*—*j*, *g*—*h*, *a*—*b*, and *m*—*n*, respectively, Fig. 1. Fig. 6 is a front view and Fig. 7 is 85 a plan of the improved furnace. Fig. 8 is 90 a vertical section taken on the line *c*—*d*, Fig. 4. Fig. 9 is a detail view, drawn to a larger scale, illustrating the method of fitting together the regenerator cylinders hereinafter referred to. Fig. 10 is a detached 95 sectional view of bands shown in Fig. 9.

The improved furnace comprises four distinct parts hereinafter described viz:—a principal furnace A, a chimney B combined with a regenerator, a reservoir or 95 fore-hearth C receiving the fused metals which are therein treated, with the usual reagents to carbonize or decarbonize the iron according to the desired qualities of the metal to be produced, and a furnace D for 100 the preliminary heating of the said re-agents.

The part A comprises a cast iron base supported by pillars 1. On this base is set a tower built up exteriorly of ordinary brick 105 masonry and lined with refractory material. This tower is bound with iron bands or hoops to protect it against exterior influences.

Between the wall of ordinary masonry 110

and the wall of refractory material, at the lower part, is an annular chamber 2, with metal walls, the said chamber, for convenience of construction, being divided into 5 several parts, and this chamber communicates with the interior of the tower through twyers. Commencing from this chamber and extending between the two walls are iron tubes 3 which moreover provide means 10 of communication between the said chamber and a second annular chamber provided in the upper part of the tower, below the feed opening 4, and thus serve as a brace work for the tower itself. This upper chamber is 15 divided into two separate concentric chambers 5, 6. The outer chambers 5 communicate through the tubes 3 with the chambers 2. The interior chambers 6 communicate through the conduits 7 with the interior of 20 the furnace through apertures 8. These chambers 5, 6 respectively communicate with channels 9, 10 formed in two tubular pillars arranged on opposite sides of the feed opening. The outer wall of the channel 25 9 is formed of masonry covered with sheet metal, and the walls of the channel 10 as well as those of the channel 9 are of metal (cast iron or the like). The channels 9, serve as conduits for the gas escaping 30 from the furnace A through the apertures 8 and the channels 10 serve as conduits for the air supplied to the twyers. Between the said pillars, in which these channels are formed, feed doors or charging mouths 15 35 are provided. The said tubular pillars are connected at their upper ends by concentric chambers 16 and 17 on which regenerator cylinders 12 and a stack or chimney 13 are supported. The space surrounded by the 40 said chambers 16 and 17 constitutes the entrance to the chimney. The chamber 17 communicates by means of the channels 10 with the apertures 8, and the chamber 16 communicates through the channels 9, chambers 45 5, tubes 3, and chamber 2 with the twyers. The chamber 17 is furnished with openings 18 through which the inflammable gases drawn out from the furnace A through the apertures 8 are delivered into the chimney 50 above the feed doors 15 where the said gases ignite on mixing with the atmospheric air drawn in through the said doors. The openings 18 may be furnished with dampers (not shown), to regulate the exit of the gases. 55 This arrangement serves two purposes:— Firstly: The gases which are still combustible are not extinguished since they are not cooled by the cold materials introduced through the feed opening; it thus results 60 that the complete calorific value of the gases is utilized. Secondly: Since the gases burn in the interior of the chimney, the workers engaged in feeding the furnace are protected from flames burning at the furnace mouth 65 and this, in addition to being hygienic and

humane, has the advantage that the controlling and the feeding of the furnace can be carried out with greater diligence and can be controlled in a better manner than heretofore with consequent advantage both to 70 the workers and to the manufacturer.

The chamber 16 communicates with the regenerators provided in the part B. These regenerators comprise a series of metal cylinders 12 within which the gases rising from 75 the furnace burn as they pass through, while air admitted to the annular chamber 20 through the opening 21, which puts this chamber in communication with a fan, passes outside these cylinders. The air for 80 combustion supplied to the twyers enters through this opening, and passes through chambers 22 inclosed exteriorly by a masonry wall protected by sheet iron and, interiorly, by the walls of the said cylinders 85 12 themselves. These chambers 22 are divided one from the other by horizontal plates whereby the air, in order to pass from one chamber to another, is obliged to travel through tubes 23 against which the burning 90 gases impinge in passing through the cylinders 12. As the tubes 23 are of a horse-shoe shape they are quite free to expand in every direction and thus can be subjected to very high temperatures without danger of being 95 deformed or broken.

Each of the regenerator cylinders above mentioned corresponds to an element of the regenerator which may comprise several such elements. The said cylinders are provided at their upper and lower ends with projecting rims or lips 32 fitted in two U-shaped iron bands 33 secured together by bolts 34 to form a ring which unites the lower rim of one part to the upper rim of 100 the other part. All the component parts are in the rough (just as they are cast), and, in order to prevent leakage at the joints the U-shaped iron bands are packed with refractory material 35. 110

A butterfly valve 24 is employed to regulate the draft through the chimney.

The fore-hearth or reservoir C is a cylinder lined internally with refractory material and put into communication with the pre-heating furnace D, through a conduit 26. 115

The fused metal is drawn off through a tapping spout 27 and the slag is discharged through the opening 28. A channel 25 serves to discharge the liquid metal from the 120 furnace A into the reservoir C, and also provides a conduit for the gases that go from A through C, to the auxiliary furnace D for the purpose of pre-heating the reagents therein. The reagents thus heated become 125 fluid or soft and in this condition fall into the reservoir C where they combine with the molten metal from the furnace A. Since this channel 25 is tangential to the periphery of the reservoir C (see Fig. 4) and on ac- 130

count of the speed of the gases, the liquid metal is subjected to a rotary movement which facilitates purification and mixing. This arrangement also serves better to eliminate the slag. The roof of the reservoir can be raised in order to facilitate the repair of the damage arising during or occasioned by the operation of the furnace.

The furnace D is a cylinder of refractory material reinforced with iron, and rises parallel to the axis of the principal furnace, as far as the charging level. Here it is closed by a cover 29 which can be opened for the introduction of the materials to be heated.

A pipe 30 commencing below this cover serves for the discharge or escape of the gases coming from the furnace D, and conducts these gases to the regenerator and the chimney B. By this arrangement, since the thoroughfare through the furnace A is partly choked by the materials therein, a part of the gases from this furnace pass through the reservoir C and escape through the furnace D, so that the pressure of air in the zone of fusion is minimized. It is known that while it is necessary to have a strong pressure and consequently a high speed of the air in the combustion zone, such a condition in the fusion zone is, on the contrary, a cause of harm. Ordinarily in blast and cupola furnaces a difference of pressure is obtained by giving a relatively small diameter to the furnace in the combustion zone while the furnace is enlarged in the zone of fusion. The result of this arrangement is however transitory since after a short time in the operation of the furnace the ratio between the cross-section of the furnace at these zones, on account of the partial fusion of the refractory material, becomes somewhat modified since the cross-section in the combustion zone is enlarged while that in the fusion zone remains unchanged. On the contrary it is evident that by the present improved arrangement the combustion zone will receive the air with all the pressure necessary and one part will pass through the fusion zone with a diminished pressure while the other part will pass into the furnace D and escape through the conduit 30 where a valve is provided by the adjustment of which the difference of air pressure in the two zones can be regulated. A gate is provided for cleaning the said furnace D and to permit the materials in the reservoir C to be stirred by means of suitable paddles.

Having now particularly described and ascertained the nature of the said inven-

tion and in what manner the same is to be performed, I declare what I claim is:—

1. A furnace for the production of iron and steel comprising a principal furnace, a shaft or chimney above said principal furnace, and a regenerator in said chimney in combination with a fore-hearth; a furnace adapted to pre-heat reagents; and a connection between said pre-heating furnace and said principal furnace adapted to conduct hot gases from the latter to the former, substantially as described.

2. A furnace for the production of iron and steel comprising a principal furnace, a shaft or chimney above said principal furnace, and a regenerator in said chimney comprising a cylinder having curved tubes 23 therein through which air to be heated is adapted to pass, in combination with a fore-hearth; a furnace adapted to pre-heat reagents; and a connection between said pre-heating furnace and said principal furnace adapted to conduct hot gases from the latter to the former, substantially as described.

3. A furnace for the production of iron and steel comprising a principal furnace, a shaft or chimney above said principal furnace, and a regenerator in said chimney, provided with means for drawing combustible gases from said principal furnace below its charging mouth, said means adapted to deliver said gases to said chimney above the feed doors of said furnace, in combination with a fore-hearth, a furnace adapted to pre-heat reagents; and a connection between said pre-heating furnace and said principal furnace adapted to conduct hot gases from the latter to the former, substantially as described.

4. A furnace for the production of iron and steel comprising a principal furnace, a shaft or chimney above said principal furnace, and a regenerator in said chimney, in combination with a fore-hearth, a furnace adapted to pre-heat reagents; means for conducting a portion of the hot gases from the fusion zone of the principal furnace to the pre-heating furnace; and means for discharging said hot gases from the pre-heating furnace into the chimney, whereby the pressure in the fusion zone is reduced and the heat of the evolved gases is utilized, substantially as described.

In witness whereof I have hereunto set my hand in presence of two witnesses.

FRANCESCO RESINELLI.
